UNITED STATES PATENT OFFICE.

FRANK C. TEGETHOFF, OF CLEVELAND, OHIO.

METAL ROOFING.

SPECIFICATION forming part of Letters Patent No. 334,624, dated January 19, 1886.

Application filed October 28, 1885. Serial No. 181,198. (No model.)

To all whom it may concern:

Be it known that I, FRANK C. TEGETHOFF, of Cleveland, in the county of Cuyahoga and State of Ohio, have invented certain new and useful Improvements in Metal Roofing, of which the following is a specification.

This invention relates to metal shingles provided with felt lining for roofing purposes; and it consists of sheet-metal plates having 10 combined therewith sheets of roofing-felt, forming shingles, which are constructed and applied to the roof, as hereinafter fully described, and pointed out in the claims.

In the accompanying drawings, Figure 1 is 15 a view showing some of my improved felt-lined metal shingles as seen when laid upon a roof. Fig. 2 is a sectional view showing the method of laying these shingles, and interlocking their felt linings. Fig. 3 is a sectional view showing 20 the interlapping of the upper edges of the felt lining with the central lock of the overlying sheets. Fig. 4 is an under-side view of one of the shingles, showing the method of attaching the felt lining thereto.

25 A is a sheet of metal of suitable size and form, and B is a sheet of roofing felt or paper, the size of which is somewhat greater than the metal sheet. The two side edges and the lower edge of the metal sheet are folded over, and in 30 said folds are embraced the edges of the sheet of felt, thus securing the felt lining to the metal. The left-side fold of the metal sheet has a return-fold, a, which projects a short distance beyond the edge of the sheet. The 35 right-side fold of the felt, also, has a return-fold, b, which projects considerably beyond the edge of the metal. The upper edge of the felt also projects considerably beyond the upper edge of the metal. Across the central 40 part of the felt lining is cut a slot to form a

flap; C, and the side projecting piece of the lining has a slit, d, cut in line with said flap C.

The method or plan of laying these metal and felt lined shingles is as follows: First, a double row of them is laid along the edge or 45 eaves of a roof, in like manner to ordinary wooden or slate shingles, with the projecting edge of the metal *a* underlying the edge of the adjoining sheet and overlying the projecting edge of the felt sheet, as seen by dotted lines 50 in Fig. 1. These sheets are secured to the roof by nails driven through their upper part, in like manner to slate or other shingles. The second and all succeeding rows are laid, as shown in Fig. 1, breaking joints like slate or 55 other shingles. In thus laying them the top projecting edges *b* of the felt linings are turned down over onto the metal, and the flaps C are slid up in under said folds, as seen at E, Figs. 2 and 3, thereby interlocking the felt lining 60 together, thus laying the shingles in even regular rows, with the linings closely interlocked, making tight compact joints.

Having described my invention, I claim—

1. The metal-roofing shingle A, provided 65 with a felt lining, B, having side and end projections and central cross-cut flap, C, substantially as described.

2. In metal roofing, the combination of the metal shingles A, provided with felt linings 70 B, having side and end projections and central cross-cut flap, C, said shingles being laid in rows, with their side edges lapping and their upper edges interlocked with the central flap, substantially as described.

FRANK C. TEGETHOFF.
